United States Patent Office

Des. 222,559
Patented Nov. 2, 1971

222,559

WASTE RECEPTACLE OR THE LIKE

Mary D. Nichols, 1251 Campbell Circle, and Beatrice D. Patrinely, 1551 Boulevard, both of Jacksonville, Fla.
32207

Filed May 28, 1970, Ser. No. 23,201

Term of patent 14 years

Int. Cl. D7—99

U.S. Cl. D49—35

FIG. 2

FIG. 1

FIG. 4

FIG. 3

FIG. 1 is an elevational view of a waste receptacle or the like, showing our new design;

FIG. 2 is a vertical sectional view taken on line 2—2 of FIG. 1;

FIG. 3 is a top plan view; and

FIG. 4 is a bottom plan view thereof.

We claim:

The ornamental design for a waste receptacle or the like, substantially as shown.
